GARMENT STRETCHER

Anton J. Mueller and Peter W. Mueller,
St. Louis, Mo.

Application August 29, 1938, Serial No. 227,361

7 Claims. (CL 287—58)

This invention relates to a garment stretcher of the insertable type and is more particularly intended for use in keeping the legs of trousers in shape, and in re-shaping the legs of laundry trousers, although devices of the approximate form may be constructed for use in stretching garment sleeves and the like.

The primary object of the invention is to provide an improved expandable and contractible stretcher which is made of a pair of like-formed adjustably secured frame parts.

Another object is to provide a garment stretcher of a pair of like-formed frame parts and with improved cooperating adjustably secured means thereon.

A further object is to provide a garment stretcher with curved crease forming parts which under tension, become straightened.

Other objects and advantages will appear as this description progresses and by reference to the drawing, in which:

Figure 1 is a side elevation of this improved garment stretcher.

Figure 2 is an end elevation of Fig. 1 taken in the direction of the arrow 2.

Figure 3 is an enlarged inverted horizontal elevation taken in the direction of the arrow 3.

Figure 4 is an enlarged transverse sectional elevation taken approximately on the line 4—4 of Fig. 1.

Figure 5 is an enlarged transverse sectional elevation taken approximately on the line 5—5 of Fig. 1.

Figure 6 is a side elevation of the pair of frame parts used in making the garment stretcher.

Referring by numerals to the accompanying drawing, 7 designates the garment stretcher which is made of a pair of frame parts 8 and 9, the part 8 having right angular extensions 10 and 11 and the part 9 having right angular extensions 12 and 13, as more clearly shown in Fig. 6, which shows the disassembled frame parts 8 and 9.

The frame parts are preferably made of flat resilient steel and each of the extensions 10 and 13 of respective parts 8 and 9 on a side face thereof, is provided with a kinked portion 14 to form an inclined cam surface 15, and formed on a side face of each of the extensions 11 and 12 of respective parts 8 and 9 is a roughened surface 16, which may be made by cross-hatching or grooving a side face of respective extensions 11 and 12.

The extensions 10 and 12 of respective parts 8 and 9 when mounted together, are adapted to have side face contact while the extensions 11

and 13 will have similar sliding contact, and for holding the cooperating pairs of extensions in sliding contact, a pair of sleeves 17 and 18 are mounted over the cooperating pair of extensions 10 and 12, and a pair of sleeves 19 and 20 are mounted over the pair of cooperating extensions 11 and 13. The sleeve 17 is fastened to the end of the extension 10 of the part 8, and the sleeve 18 is fastened to the end of the extension 12 of the part 9. The sleeve 19 is fastened to the end of the extension 11 of the part 8 and the sleeve 20 is fastened to the end of the extension 13 of the part 9, the fastening or securing of the sleeves to the respective extensions, being by punching portions thereof in respective extensions, as indicated at 21 in Fig. 5.

Before securing the sleeves to the respective extensions, a slidable locking ring 22 is mounted over respective pairs of extensions, each locking ring when slid on cooperating pairs of extensions, 20 being adapted to frictionally clasp the cooperating pairs of extensions so that they will be held against sliding relative to one another, and said locking rings also serving to release the frictional contact so that the extensions may slide relative 25 to one another.

In use, it is preferable to have a pair of garment stretchers 7 as shown, one for each trouser leg, and in engaging a stretcher in respective legs, the narrow end A of the stretcher is inserted at the 30 waist of the trousers B while the stretcher is in a contracted form. After the insertion of a stretcher in a trouser leg, the overlapping pair of angular extensions 10 and 11 are moved outwardly from one another until the trouser leg at that end is 35 made relatively taut on opposing parts thereof, where the creases are to be formed, and while being so held, the over-engaging locking ring 22 is shifted into engagement with the cam surface 15 on the kinked portion 14 of the extension 10, 40 and the inner periphery of the locking ring will frictionally engage the cam surface 15 and the roughened surface 16 on the extension 12, thereby holding the overlapping extensions 10 and 12 in gripped engagement against slipping.

The wide end C of the stretcher 7 having the overlapping extensions 11 and 13 are then moved outwardly relative to one another to create tautness across the upper end of the trouser leg, and the locking ring 22 is secured into frictional engagement with the cam surface 15 of the extension 13 and the roughened surface 16 of the extension 11 for securely holding the extensions 11 and 13 against slipping.

For removal of this improved garment stretcher, 55

respective locking rings 22 are dis-engaged from respective cam surfaces 15, thereby providing sliding release of the respective pairs of extensions 10-12 and 11-13.

5 Obviously, the flat steel material from which the garment stretcher is made, is preferably of non-rust and stainless material, as the garment stretcher in addition to being used for holding the garment legs in shape, can be used in garments 10 which are laundered, and are held by the stretchers during the drying process.

From an inspection of Fig. 6, the leg portions 23 of respective frame parts 8 and 9 are bowed outwardly their entire length, and the reason 15 therefor, is to provide a structure whereby when the stretcher 1 is in expanded position in a trouser leg, the tautness of opposing sides of the trouser leg will approximately straighten the bows 23 into the positions shown in Fig. 1, so as to provide 20 relatively straight creases as the garment stretcher is made of resilient flat metal.

Having thus described the invention so that those skilled in the art will be able to practice the same, what we desire to secure by Letters 25 Patent is defined in what is claimed, it being understood that various changes in the device shown and described above in detail and not amounting to invention, may be made without departing from the spirit and scope of our invention.

30 What we claim is:

1. An adjustable joint for a garment stretcher having a pair of frame members, comprising extensions on each frame member, means for holding the extensions in overlapped relation, means 35 for maintaining part of one of said extensions in diverging relation from the other extension, said means substantially spaced from the end of said extension, a slide embracing said extensions between the end thereof and said diverged part 40 and movable therealong toward and away from said diverged part, the internal dimension of the slide being less than the maximum exterior divergence of said overlapping extensions.

2. An adjustable joint for a garment stretcher 45 having a pair of frame members, comprising extensions on each frame member, means for holding the extensions in overlapped relation, means for maintaining part of one of said extensions in diverging relation from the other extension, a 50 slide embracing said extensions and movable therealong toward and away from said diverging part, the internal dimension of the slide being less than the maximum exterior divergence of said overlapping extensions, said slide being disposed on the side of said diverging means which 55 is approached by the diverging means when the frame members are moved toward each other.

3. An adjustable joint for clothing stretcher bars and the like, comprising a pair of adjacent, 60 relatively slidable sections, an intermediate portion of at least one of said sections being directed toward the other section to provide a resilient wedge-shaped portion between sections, and at least one separate sliding thimble snugly 65 rounding the sections where the sections are closely adjacent to one another between the

wedge shaped portion and the free end of the section in which the same is arranged, said thimble being adapted to slide over said wedge-shaped portion to effect a frictional grip between the sections.

4. An adjustable joint for clothing stretcher bars and the like, comprising a pair of relatively slidable sections having adjacent portions, means on one of said sections arranged to maintain said sections in spaced relation to each other at a neighboring region, said means being spaced from the end of said section, a separate slidable annulus closely surrounding the said sections at their adjacent portions between the spacing means and the free end of the section containing the same, said annulus having an interior diameter less than the maximum distance between the opposite exterior surfaces of said sections at the spaced regions thereof, and said annulus being arranged to slide over said adjacent portions and onto the spaced regions of said sections to frictionally grip the sections together with the annulus.

5. An adjustable joint for clothing stretcher bars and the like, comprising a pair of adjacent relatively slidable sections, an intermediate portion of at least one of the sections being directed away from the other section to provide a cam surface sloping toward the free end of said section, and at least one separate sliding annulus 25 closely surrounding said sections where the sections are closely adjacent one another, said annulus being adapted to slide onto said sloping cam surface to effect a frictional grip between the sections.

6. An adjustable joint for clothing stretcher bars and the like comprising a pair of relatively slidable resilient metal sections having flat surface portions in close adjacency, an intermediate portion of one of said sections being bent out of alignment with said closely adjacent portions to provide a region whereat the sections are spaced from each other; a separate slide closely embracing said sections at their adjacent portions between said bent portion and the free end of said section and arranged to be moved onto said spaced region, the internal diameter of said slide being less than the maximum distance between the opposite exterior surfaces of said portions at the spaced region.

7. An adjustable joint for clothing stretcher bars and the like, comprising a pair of adjacent relatively slidable sections of flat metal stock, a portion of at least one of said sections being deformed to provide a cam surface sloping in the direction of advance thereof when said sections are relatively moved to collapse the clothing stretcher, and a sliding annulus surrounding said sections on the side of said deformed portion toward which said sloping cam surface advances 50 when said sections are relatively moved to collapse the clothing stretcher, said annulus being adapted to slide onto said sloping cam surface to effect a frictional grip between sections.
